Primary Examiner — Selina Sikder

(74) **Attorney, Agent, or Firm:** Volpe and Koenig, P.C.

(57) **CLAIM**

We claim, the ornamental design for a remote controller for air conditioner, as shown and described.

DESCRIPTION

FIG. 1 is a front, top and left side perspective view of a remote controller for air conditioner according to our new design;

FIG. 2 is a front view thereof;

FIG. 3 is a left side view thereof;

FIG. 4 is a right side view thereof;

FIG. 5 is a top plan view thereof;

FIG. 6 is a bottom plan view thereof; and,

FIG. 7 is a rear view thereof.

1 Claim, 5 Drawing Sheets
